CLAIM

The ornamental design for a storage device, as shown and described.

DESCRIPTION

FIG. 1 is a front perspective view of a storage device showing our new design;

FIG. 2 is a top view thereof;

FIG. 3 is a bottom view thereof;

FIG. 4 is a front view thereof;

FIG. 5 is a rear view thereof; and

FIG. 6 is a right side view thereof, the left side being a mirror image;

FIG. 7 is a front perspective view of another storage device showing our new design;

FIG. 8 is a top view thereof;

FIG. 9 is a bottom view thereof;

FIG. 10 is a front view thereof;

FIG. 11 is a rear view thereof; and,

FIG. 12 is a right side view thereof, the left side being a mirror image.

The broken line showings are included for the purpose of illustrating portions of the storage device and form no part of the claimed design.

1 Claim, 8 Drawing Sheets
